UNITED STATES PATENT OFFICE

148,068

DESIGN FOR AN INFANT'S CHAIR

John E. Huber, Cincinnati, Ohio

Application September 3, 1946, Serial No. 133,024

Term of patent 14 years

(Cl. D15—1)

To all whom it may concern:

Be it known that I, John E. Huber, a citizen of the United States, residing at Cincinnati, county of Hamilton, and State of Ohio, have invented a new, original, and ornamental Design for an Infant's Chair, of which the following is a specification, reference being had to the accompanying drawings forming part thereof.

In the drawing,

Figure 1 is a front perspective view of an infant's chair showing my new design, and

Figure 2 is a rear perspective view of the infant's chair illustrated in Figure 1.

My design of an infant's chair is characterized by the tray adjustably mounted upon a centrally disposed support, the tray being independent of the side arms, the design including an adjustably supported foot rest.

I claim:

The ornamental design for an infant's chair, substantially as shown and described.

JOHN E. HUBER.
